UNITED STATES PATENT OFFICE.

LEON KLEIN, OF BROOKLYN, NEW YORK.

KNITTING-MACHINE ATTACHMENT.

Application filed December 16, 1924. Serial No. 756,289.

To all whom it may concern:

Be it known that I, LEON KLEIN, a citizen of the United States, residing at Brooklyn, in the county of Kings and State of New York, have invented certain new and useful Improvements in Knitting-Machine Attachments, of which the following is a specification.

My invention relates to an attachment to a knitting machine (and more particularly to a full-fashioned flat knitting machine of the "Cotton" type) for knitting into stockings various predetermined designs, or combinations of designs, thereby accomplishing the same results that are obtained by the more expensive "Fancy" knitting machines.

The principal object of the invention is to provide a simple, efficient and comparatively inexpensive striping mechanism that may be readily attached to a knitting machine of the character described, without change of construction or operation of the machine parts, whereby artistic and novelty designs or fancy work may be produced.

Although the knitting machine that is equipped with my improved attachment functions to accomplish the result stated, yet plain knitting alone may, of course, be produced, at the will of the operator.

My design-knitting attachment is applied to a machine that is large and complicated, and I have, therefore, purposely omitted from the drawings and description thereof many well known parts, excepting the devices for producing the portions of stockings on which the designs are customarily made.

In the drawings, forming part of this specification:

Figure 1 is a front elevation of one end of a plain, full-fashioned knitting machine, of the character indicated, equipped with my attachment;

Figure 2 is a view in end elevation thereof;

Figure 3 is a fragmentary view in rear elevation thereof;

Figure 4 is a vertical sectional view taken on the plane of the section line 4—4, Fig. 3, looking in the direction of the arrows indicated thereon.

Figure 5 is also a vertical sectional view taken on the plane of the section line 5—5, Fig. 3, looking in the direction of the arrows indicated thereon;

Figure 6 is a fragmentary sectional view

taken on the plane of the section line 6—6, Fig. 5;

Figure 7 is a fragmentary sectional view taken on the plane of the section line 7—7, Fig. 5;

Figure 8 is a vertical sectional view taken on the plane of the section line 8—8, Fig. 3, looking in the direction of the arrows indicated thereon;

Figure 9 is a vertical sectional view taken on the plane of the section line 9—9, Fig. 8, looking in the direction of the arrows indicated thereon;

Figure 10 is a fragmentary horizontal sectional view taken on the plane of the section line 10—10, Fig. 8, looking in the direction of the arrows indicated thereon;

Figure 11 is a horizontal sectional view taken on the plane of the section line 11—11, Fig. 4, showing the extreme outward position of the slur bar with respect to certain tripping mechanism;

Figure 12 is a similar view, a certain structural element being broken away, showing the slur bar in the reverse position;

Figure 13 is a detail sectional view on the plane of the section line 13—13, Fig. 12, looking in the direction of the arrows indicated thereon;

Figure 14 is a detached view, in perspective, of the actuating mechanism for the complemental pattern-wheels;

Figure 15 is an enlarged sectional view on the plane of the section line 15—15, Fig. 1, looking in the direction of the arrows indicated thereon, and showing the carrier-frame in its lowered position;

Figure 16 is a view similar to Fig. 15, but showing the carrier-frame raised;

Figure 17 is a view in front elevation of one of the carrier-frames, parts being shown broken away;

Figure 18 is a top plan view of a portion of one of the carrier-frames, looking in the direction of the arrow 18 indicated on Fig. 15;

Figure 19 is a view in perspective of a portion of the mechanism for tripping or releasing the supplemental thread-carriers to permit them to move to inoperative position;

Figures 20 and 21 are detached detail views, in perspective, of certain constructional parts related to the supporting means for the supplemental thread-carriers;

Figure 22 is a detached detail view, in

perspective, of a part related to the re-setting means for the supplemental thread-carriers;

Figure 23 is a detached detail view, in perspective, of one of the supplemental thread-carriers;

Figure 24 is a detail view, in front elevation, of the hand-actuated means for tripping the supplemental thread-carriers, and showing the tripping-bar, the carrier-rod, a supplemental thread-carrier, and the supporting means for the latter broken away;

Figure 25 is a sectional view taken on the plane of the section line 25—25, Fig. 24, looking in the direction of the arrows indicated thereon;

Figure 26 is a similar view taken on the plane of the section line 26—26, Fig. 24; and

Figure 27 is a diagrammatic illustration of the pattern-wheels and the pins carried thereby to effect the design shown at the right in said figure.

My invention, briefly described, comprises, generally, a pair of complementary pattern-wheels A, a chain-motion B, and a narrowing-device C.

With special reference to Figs. 3 to 7 inclusive of the drawings, 10 and 11 indicate twin, rotatable pattern-wheels pivotally mounted between a pair of enlarged hubs 14, 14 located toward the upper ends of parallel, spaced, upward-projecting arms 12, 12 forming part of a casting or supporting member 9 carried by the upper beam 13 of the knitting machine frame 1. As shown, the casting and the arms are, from the point of connection of the former with the beam 13, curved rearwardly and upwardly to the hubs 14, through which passes the axle 15 of the pattern-wheels.

On the outer face of each of the pattern-wheels 10 and 11, which, as shown, are disposed face to face, is a concentric series of threaded openings 16, into which are screwed projections, such as pins 17, of varying lengths, depending upon the desired designs or patterns to be embodied in the stocking. It is advisable, of course, to use a relatively large number of pins and preferably of a number that is divisible by the greatest number of factors.

Each pattern-wheel is provided, peripherally, throughout the circumference thereof, with transverse, spaced grooves 24, the total number of which is the same as that of the pins 17, for engagement by pawls 31 and 32 for actuating said wheels alternately in a step-by-step manner.

To prevent accidental movement of the pattern-wheels 10, 11, there may be provided, in the head portion of the casting or supporting member 12, spring-pressed locking pins 186 (Figs. 1 and 5) adapted to engage the grooves 24. A relatively short

hand-lever 187 is fulcrumed on the outer end of the casting, for disengaging the locking-pins 186 with respect to the pattern-wheels 10, 11, when desired, as when it is necessary to remove said wheels, or for any other purpose.

For the purpose of steadyng the pattern-wheels, I provide the supporting-members 12, 12 with a pair of inwardly-extending bearing lugs 25, 25, which lightly contact with the outer faces of said wheels, adjacent the periphery thereof.

Adjacent the pattern-wheels and disposed transversely thereof is a plate 18 provided with a longitudinal groove 18^a through its lower edge for the reception of one end of the front, reciprocating carrier-rod 19. Suitable fastening means 20 secure the rod to the plate. If desired, it is obvious that said carrier-rod 19 and plate 18 may be integral. The plate is provided, laterally, with upward-projecting ears 20^a. The plate 19 with the arms 20^a, 20^a constitute a yoke portion carried by the rod 19. The ears are provided, on their opposing faces, with threaded openings for the reception of oppositely-disposed screws 21, 22; but these screws may be omitted, if desired, as they are not indispensable. Lock nuts 23 may be utilized to prevent accidental displacement of the screws, after adjustment thereof.

It will be readily seen (see particularly Fig. 6) that the movement or stroke of the carrier-rod 19 in both directions is controlled or limited by the length of the particular pattern-wheel pins 17 which may be used, with respect to a predetermined adjustment of the screws 21, 22.

The pattern-wheel supporting members 12, 12 are provided, preferably at points immediately beneath the pattern-wheels, with rearwardly-extending arms 2, 2 connected at their ends by a cross member 26 provided with a pair of vertically-extending rectangular openings 27, in which are slidably mounted upright rods 28, 29. To the upper ends of said rods are pivotally connected, as at 30, the pawls 31, 32 adapted to engage, successively, the grooves 24 in the periphery of the pattern-wheels 10, 11. Coil springs 33 are located between the pawls and the upper ends of the rods 28, 29, to hold the pawls in constant contact with the periphery of the pattern-wheels.

To limit downward movement of the rods 28, 29, I secure thereto angle plates 34 adapted to contact with the cross-member 26. Coil springs 35 are interposed between the angle plates 34 and the cross-member 26, to return the rods 28, 29 to their lowered or normal position, after upward movement thereof by the means about to be described.

Secured to an upright 36 carried by the rear beam 57 of the knitting machine is a

casting, generally indicated at 37, comprising a horizontal top plate 38 and depending arms 39, 40 and 41. As shown in Fig. 11, the plate 38, at one longitudinal edge thereof, is recessed, as shown at 42, 42, for the reception of the lower portion of the rods 28, 29. A relatively narrow strip 43 is removably secured to one edge of the plate 38, and extends transversely across the rods 28, 29, for the purpose of preventing displacement of the latter.

The lower extremities of the rods 28, 29 are bifurcated, as most clearly shown in Fig. 14, at 3, for the reception of the reduced end portions of the latch or tripping-members 44, 45, carried by and pivoted to the rods 28, 29, as at 46. The lower ends of the dogs or latches 44, 45 are cut away to form shoulder portions 46' adapted to be engaged by a wear plate 47 carried by a block 48.

The block 48 is preferably integral with the upper end of a rod 49 slidably projecting through an opening 50 in an angular lug 51 or extension 51 integral with the depending arm 41 at the lower end thereof. Secured to the lower extremity of the slideable rod 49 is a slightly enlarged head portion 52 apertured for receiving a bolt 53, by which it is connected to one end of a rocker-arm 54. A head portion 55, similar to the head portion 52, is pivotally connected to the opposite end of the rocker arm 54, as at 56. The rocker arm 54 is fulcrumed to the rear beam 57, as at 58. A rod 59 carrying the head 55 is extended upwardly and adjustably connected with the head portion 60 of a pivotal member 61 by a set screw 4.

The pivotal member 61 passes through one end of a rocker arm 62, which is, in turn, carried by and fulcrumed at 64 to an upright bracket 63. The bracket is securely bolted to the upper edge of the rear beam 57. Near the forward end of the rocker arm 62 is a hub portion 65, through which is passed a bolt 66 for pivotally mounting a roller 67 peripherally contacting with a cam 69, having an eccentric portion 70, secured on the main cam-shaft 71 of the knitting machine. To the extreme forward end of the rocker arm 62 is secured one end of a coil spring 68, which maintains the roller 67 in constant contact with the cam 69. The coil spring 68 may be secured, at its other end, to the front portion of the frame 1 by a clip 72, or in any other suitable manner.

Adjustably secured to the rod 49, as by a set screw 5, is a collar 73 provided with an angular projection 74 having a lateral reduced portion 6, constituting a spindle or axle for a swinging dog 75, as clearly illustrated with special reference to Figs. 3, 4 and 14. A pin 76 is projected through the reduced portion 6 of the extension 74, and to one end of said pin is secured one end of a

coil spring 78, the opposite end of which is adapted to be secured, as by a pin 79, to the dog 75, toward its outer end. The spring 78 is adapted to be readily placed upon or removed from the pin 79, for the purpose presently appearing.

In Figs. 11 to 14 inclusive are illustrated my novel means for alternately actuating the pattern-wheels 10, 11, in a step by step manner, with each reciprocating motion for the knitting operation. The extreme end of the slur bar 80, which is slidably supported in grooves 7' in the free ends of brackets 7 secured at their other ends to the upper beam 13, is provided with a pair of upstanding, spaced lugs 81, 81, between which is secured a wiper strip 82, for the purpose of contacting with the end 83 of a rocker arm 84. The arm 84 is provided with an integral hub portion 85 located near the opposite end thereof, for the purpose of receiving a short shaft 86, to which it is keyed. Shaft 86 passes through the plate 38, by which it is supported, as shown most clearly in Fig. 4. The arm 84 is extended beyond the hub portion 85, as indicated at 87, which extended portion is adapted to engage a slidably mounted latch 88. Said latch is slidably mounted in a recess 89 formed in the top of a lug 90, which is upwardly extended from the plate 38 of the casting 37. The latch is provided, on its inner end, with a pair of curved recesses 91, 92, separated by a curved or humped portion 93. Said recesses and the intermediate humped portion are reversely curved, as clearly shown in Fig. 12. As is obvious from an inspection of Fig. 12, the end of the rocker arm 84 travels in contact with the curved walls of said recesses and hump.

A curved leaf spring 94 is secured to the lower side of the plate 38, and is extended upwardly and bears, at its free end, against the outer end of the latch plate 88, causing the latch member to constantly contact with the adjacent end of the rocker arm 84, to removably secure a plate 95 to the top of the lug 90, immediately above the latch 88 and transversely thereof, for retaining it in position.

For the purpose of moving one or the other of the latch or tripping members 44, 45 from the path of movement of the vertically movable block 48, I provide a bar 96 slidably mounted in suitable openings 97 located near the lower ends of the depending arms 39, 40. One end of the bar 96 is provided with an angularly bent or curved portion 98, which terminates in a rounded nose portion 99 adapted to engage and rock the latch-members, alternately, from the path of movement of the block 48. A pair of suitably spaced, upstanding pins 100 is located in the upper surface of the bar 96. Said pins are adapted to be engaged by an

4
arm 101 extending transversely across the bar 96 between said pins, said arm being keyed to the lower end of the shaft 86.

5 On the outer sides of the latch or tripping members 44, 45 are secured headed pins 102, 102, for the purpose of receiving one end of coil springs 103, 103, whose opposite ends are secured to the pins 104 carried by the arms 40, 41.

10 When it is desired that the pattern-wheels 10, 11 shall be temporarily inactive or motionless at predetermined intervals, as, for example, when knitting various designs into the stocking, I provide a novel form of chain motion, indicated generally by B. A double-toothed sprocket-wheel 105 is rotatably mounted in a hub in the outer end of the arm 106 secured to the upper beam 13 by a bolt 107. A lower sprocket-wheel 108, somewhat similar to the sprocket-wheel 105, is rotatably mounted on a stub shaft 109 integral with a hub portion 110 formed on the standard 111 bolted to the upper end of the lower beam 57.

15 An endless chain 112, made up of a plurality of looped wire portions, as is clearly shown in Figs. 8 and 9, is adapted to pass around the sprocket-wheels 105 and 108. Apertured lugs 113 are mounted on the wire cross bars 8 (constituting the links of the chain 112), in the approximate center thereof. These lugs 113, which are arranged throughout the length of the chain 112 at predetermined intervals, depending upon the particular design to be created, are provided, on their inner ends, with a flattened surface 113^a, as shown in Fig. 8, while their outer surfaces are rounded, as shown at 113^b, for the purpose of engaging the free end 114 of a lever 115. This lever is provided with a hub portion 116 in its approximate longitudinal center, which hub portion is apertured to receive a fulcrum pin 117 passing through a slot 120 in the upper angularly bent portion 118 of the arm or standard 111. By releasing a nut 119, which is screwed on the threaded end of the fulcrum pin 117, the lever 115 may be vertically adjusted within the slot 120.

20 The upper extremity of the lever 115 is provided with a horizontally disposed arm 121 adapted to extend across the latch members 44, 45 for moving them both out of engagement with, or out of the path of movement of, the vertically-movable block 48, whereby no rotative movement is imparted to the pattern-wheels 10, 11. This action, of course, takes place when the lower end 114 of the lever 115 is caused to contact with one of the lugs 113 carried by the chain 112. Intermediate the two rows of sprocket teeth in the sprocket-wheel 108, the latter is provided with an annular rib or circumferential raised portion 122, for the purpose of forming a firm seat for the rear or flattened

25 portions of the lugs 113 in their travel around said wheel, as shown in Figs. 9 and 10, whereby the lower end 114 of the lever 115 will form a more positive contact with said lugs, said lower end of the lever being disposed, as shown, adjacent said rib. To prevent the end 114 of the lever 115 contacting with the cross wires of the endless chain 112, I provide, adjacent the upper end and transversely of said lever, a stationary abutment 123, which is preferably integral with the lower portion of the arm 40 of the casting 37, as shown in Fig. 3, and which is adapted to serve as a stop for the upper end of the lever 115, for preventing its moving outward.

30 Preferably integral with the double sprocket-wheel or drum 108 is a ratchet-wheel portion 124, whose diameter is substantially the same as the sprocket-toothed portions. The number of teeth in the ratchet wheel portion 124 is the same as the number of sprocket-teeth in either one of the two series thereof in the wheel or drum 108, so that, as this wheel or drum is rotated the distance of one tooth, it will cause the endless chain 112 to be moved the distance of one link. The operation of the toothed wheel 108 is effected by the dog or pawl 75, which as has already been explained, is pivotally connected with the slidable rod 40, each movement of which is the distance of one tooth on the ratchet wheel 124.

35 When it is desired to actuate the pattern-wheels 10, 11 without actuating the chain-motion, that is to say, when a simple design is to be knitted into the stocking, the coil spring 78 is disengaged from the headed pin 79 carried by the pawl or dog 75, allowing the latter to fall to its lowered position, as illustrated in Figs. 3 and 4. Thus, it will be seen that, the sprocket-wheels 104 and 105, together with the sprocket-chain 112, remaining stationary, the lever 115 can not be actuated to move the latches 44 and 45 out of the path of movement of the block 48.

40 Figs. 15 to 27 of the drawings illustrate the various details in connection with the narrowing mechanism of a full-fashioned knitting machine of this type. In the knitting of the various predetermined designs into the stocking, means must, of course, be provided with special reference to the narrowing mechanism, so that, when the stocking is being narrowed, the designs will likewise be narrowed or terminated at those particular points. With this object in view, my invention consists of a novel form of narrowing means that is associated with the design-producing mechanism.

45 In Fig. 1 are illustrated two stocking frames, and in Figs. 15 to 27 inclusive are shown various details of one of the frames, together with the means associated with the narrowing mechanism.

The supplemental carriers 130 are similarly constructed, and each consists of a thread-carrying member 131, which is somewhat similar in construction to the usual form of thread-carrier of a machine of this type. Each thread-carrying member is connected at its upper end by a screw 132 to the strip or body portion 133, through the slotted openings 134, by which the thread-carrying portion 131 may be adjusted with respect to its carrying strip or body portion 133. The strip-portion 133 is provided, near its upper end, with a pin 135 extending transversely through the strip so as to project laterally beyond both faces thereof. A headed pin or screw 137 is located in the front of the strip 133, near its lower end, for a purpose presently appearing.

I have found from experiments that twelve supplemental thread-carriers give the best results in a frame of this type and size, and these thread-carrying strips 133 are slidably mounted in a bar or plate 138, which is provided with the required number of grooves 139 located in the front face thereof. The rear face of this bar or plate 138 is provided with an angular groove or cut-out portion 140 extending across its entire length, and is secured to the front or foremost carrier-rod 19 in any suitable manner.

The strips or body portions 133 of the thread-carriers 130 are retained within their respective grooves 139 in the bar 138 by a thin plate 143 secured by screws 144 to said bar. This plate 143 is provided along its upper edge with forwardly and downwardly bent ears or lugs 145, which are perforated for the purpose of receiving the upper end of a coil spring 146. The opposite or lower end of said spring is fastened to the headed pin or screw 137, for a purpose to be later explained. The headed pin 137, it will be seen, serves the dual purpose of fastening means for the spring 146 and of means for limiting the upward movement of the thread-carrier 130 with respect to the carrier-bar or plate 138.

In actual practice, the best results are obtained in connection with the narrowing mechanism by first releasing the end thread-carriers *a* (see Fig. 17), then releasing the thread-carriers *b*, then, as the narrowing operation proceeds, releasing two additional adjacent carriers *c*, and, finally, releasing the remaining four carriers *d*. This action is accomplished, in the example shown in the drawing, by a slidably mounted rod 147, mounted in transverse grooves 136 in the guides 148, which are carried by and secured to the front carrier-rod 19 by set screws 149. For the purpose of removing the strip or rod 147 from its guide 148, I provide a plate 150, which is suitably fastened to the guide member 148.

Secured to the strip or rod 147 is a plu-

rality of blocks or lugs 151, which are predeterminedly located upon the strip 147 and made secure thereto by screws 152. Each block or lug 151 may be provided with a recess or cut-away portion 153, so that it may be snugly fitted over the rod 147. The lower edges of these lugs or blocks 151 are adapted to coact with the rearwardly-projecting portion of the pins 135 carried by the body portions 133 of the thread-carriers 130, for the purpose of holding the latter in their downward or operative position (as shown in Fig. 26), and, when these blocks 151 are moved out of engagement with the pins 135, the thread-carriers 133 are drawn upwardly through their grooves 139 by the coil springs 146. These positions are clearly illustrated in Figs. 15, 16, 17 and 26.

The thread-carriers 130 are moved upwardly into their inoperative position, in the order already described, simultaneously throughout all of the frames by reason of the fact that all of the blocks 151 are secured to the single rod 147, which, of course, extends substantially the entire length of the knitting machine.

The movement of the rod 147, for effecting release of the thread-carriers in the particular order described, is accomplished by a manually-operated lever 154, fulcrumed on a bolt 156 to a plate 155, having an integral, lateral, grooved portion 158 removably secured to the carrier-rod 19, as by bolts 159. The lower end of the lever 154 is provided with a yoke portion 157 engaging a pin 158 carried by the slidable rod 147. The plate 155 is provided at its upper end with notches 160 arranged on an arc struck from the pivotal center of the lever 154. To prevent accidental movement of the rod 147, a spring-tensioned dog or latch 161, engageable in the notches 160, may be placed within the handle portion 162 of the lever 154. To limit endwise movement of the rod 147, I provide in the plate 155 a pair of outwardly-extending and suitably spaced pins or lugs 163 in the path of movement of the lever 154.

Slightly above and to the rear of the narrowing shaft 164, which, of course, connects the narrowing mechanism with all of the frames in the usual manner, is an auxiliary shaft or rod 165, of smaller diameter than the shaft 164. The latter shaft is supported from the curved levers or arms 166 by journal blocks 167 secured to the arms by bolts 168.

The oscillatory shaft 165 is mounted at its ends in the journal blocks 167, and extends between all of the several knitting frames for the purpose of providing a carrier resetting means for each frame. Each carrier resetting means consists of a relatively thin metallic strip 169, of sufficient length to project beyond the pins 135 of

the extreme or end carriers of each frame. Each strip 169 is supported from the shaft 165 by brackets, each of which comprises a collar 170 and an integral finger 170^a. The collar 170 is adapted to be adjustably secured on the shaft 165 by a set-screw 171.

A hand-actuated latch or finger piece 172 is secured to the shaft 165 at a convenient point, and is attached to one end of a coil spring 173. The upper end of the coil spring is (see Fig. 1) fastened to an arm 174 integral with a strip 175, which is secured to the front face of the journal blocks 167. The upper extremity of the strip 175 is (see Fig. 2) provided with an angular bent portion 175^a for supporting a strip 176, which is suitably perforated for the reception of the independent threads 177, employed in producing the fancy designs. By depressing the latch or finger piece 172, the rod 165 is oscillated, thereby changing the position of the entire group or gang of strips 169 simultaneously from the position shown in Fig. 15 to the other extreme position illustrated in Fig. 16. By releasing the pressure from the finger piece 172, the coil spring 173 returns the rod 165 and the gang of strips 169 to their normal position, or to the position as shown in Fig. 15.

With special reference to Figs. 1 and 2, 178 indicates the well known lever for raising the entire narrowing mechanism out of its operative position with respect to the needles, which operation, of course, becomes necessary when inserting either the welting or topping bar into the machine. Briefly described, the bell-crank portion of the lever 178 is connected to one end of a rod 179, which is, in turn, connected to the free end of a lever 180 secured to its respective rock shaft 181. Secured to this rock shaft is a lever 182 provided on its outer end with a roller 183 engaging the cam-lifting lever 184, to which is pivotally mounted the lower end of the rod 185, the upper end being adapted to receive and support the narrowing shaft 164. I utilize this narrowing mechanism lifting device in connection with the means for resetting the supplemental thread-carriers 181 from their inoperative position, as indicated by dotted lines in Fig. 15, to their operative position, as shown in full lines and as will be hereinafter more fully described.

Fig. 27 illustrates a diagrammatic view of the pattern-wheels 10, 11 and their respective design-creating pins 17, and a like showing of the design, shown at D, which would be created by my attachment when the pins 17 are of the relative proportions shown. This design would, of course, be independent of the chain motion mechanism.

Having fully described the various parts of my improved attachment, the operation thereof will be readily grasped.

When it is desired to operate my attachment in conjunction with the knitting machine for simple designing, that is to say, without the use of the chain motion B, the coil spring 78 is disengaged from the pin 79 carried by the dog or pawl 75, and the latter is disengaged from the ratchet-wheel 124, as illustrated in Figs. 3 and 4.

The rotation of the cam 69, in tilting or rocking the lever 62 against the tension of the coil spring 68, tilts or rocks the lever 54 through the medium of the rod 59 to move the rod 49 upward a predetermined distance within its bearing 51. The block 48, carried by such upward-moving rod 49, when engaging one of the tripping-members 44, 45 carried by their respective rods 28 and 29, will, of course, rotate the corresponding pattern-wheel 10 or 11 the distance between two of the spaced pins 17. The pattern-wheels 10 and 11 are caused to rotate successively, in a step by step manner, by reason of one or the other of the tripping-members 44 or 45 being in the path of movement of the movable block 48, as has already been explained.

The tripping-members 44, 45 are alternately rocked out of the path of upward movement of the rod 49, in timed relation with the latter's movement, by the slur-bar 80 actuated mechanism previously described.

The varying lengths of the particular pins 17 which have been assembled with the pattern-wheels 10, 11 govern the travel or reciprocation of the carrier-rod 19. The shorter the pins, the longer will be the stroke of the carrier-rod.

When it is desired to actuate the chain motion B in connection with the pattern-wheels A, the dog 75 is placed in engagement with the ratchet-wheel 124. The vertical movement of dog, which is carried by the vertically-movable rod 49, will now rotate the endless chain 112 the distance of one link at each downward movement of such dog. The lugs 113 carried by the links of the chain 112 at predetermined distances thereon depending upon the desired design, will, in the movement of the chain, be brought into contact with the end 114 of the lever 115, thereby rocking said lever and, by the projection 121, swinging both tripping members 44, 45 out of the path of movement of the movable block 48. The parts are so timed in their movements that the tripping members 44, 45 are moved out of the path of movement of the block when the rod 49 is on its downward stroke, so that, at the next upward reciprocation of said rod, the pattern-wheels 10, 11 will not be actuated.

With each stroke of the slur-bar 80, the pivoted arm 84 is moved in either one or the other direction, for the purpose of shifting the bar 96 out of engagement with one trip-

ping-member 44 or 45 and into engagement with the other, for the purpose of swinging them alternately out of the path of movement of the vertically movable block 48, so that but one pattern wheel will be operated at a time.

Referring to the supplemental thread-carriers and their relation to the narrowing mechanism, with particular reference to Figs. 15, 16 and 17: When the design is being formed in the full width of the stocking, the entire series or gangs of the supplemental thread-carriers is in its lowered or operative position, as shown in full lines in Fig. 15, for feeding the thread across the entire width of the stocking. When the narrowing process begins, the machine is stopped and the extreme end carriers *a* of each frame section are raised by means of the handle 162, and its associated thread is severed close to the stocking and secured in the usual manner by the operator. As the narrowing process proceeds, another pair of thread-carriers *b* is likewise raised by a further movement of the lever 162 and their respective threads secured. This action is continued throughout the narrowing operation of the stocking until the last series of four supplemental carriers *d* are raised out of operative position. At this time, the hand-lever 162 has been moved over to its extreme right.

When it is desired to reset the supplemental carriers to their lowered or operative position, the entire carrier mechanism is lifted out of engagement with the lower handles by means of the hand lever 178. When the narrowing mechanism is in its raised position, the hand-actuated finger piece 172 is depressed, as shown in Fig. 16, thereby causing the re-setting strip 169 to bear against the upper end of each of the thread-carriers, the lower edge of these strips being immediately above the short pins 135 carried by the body portion of the thread-carriers.

With the finger piece 172 still depressed against the tension of the coil spring 173, the hand-lever 178 is now lowered, permitting the narrowing mechanism to descend to its operative position. This action, it will be seen, causes the lowering or re-setting of the entire series or groups of supplemental thread-carriers 130, by reason of the lower end of the strips 169 exerting a downward pressure upon the pins 135, against the tension of the springs 146. In this position of the thread-carriers, with the finger-piece 172 still depressed, the hand lever 162 is now moved to its extreme left position against the stop in 163, causing the blocks 151, which are carried on the strip 147, to obstruct the path of vertical movement of the pins or extensions 136 carried by the upper end of the thread-carrier, shank

or body portion 133. This position is clearly shown in Fig. 26. At this point, the finger piece 172 is permitted to return to its raised position, releasing the strip 169 from the pins 135 and permitting the pins 135 to bear against the lower edge of the blocks 151, remaining in this position until the rod 147 is shifted from time to time, again causing the blocks to slide out of the path of contact with the pins 135, when it is desired to effect narrowing, as has already been described.

What I claim as new and desire to secure by Letters-Patent is:

1. In a knitting machine, mechanism for producing striping designs or patterns in hosiery, including a reciprocating carrier-rod equipped with thread-carriers, a pattern wheel for limiting the movement of the carrier-rod in one direction, a similar wheel for limiting the movement of the carrier-rod in the other direction, each wheel being adapted to carry an annular series of removable pins of differing lengths, and means for independently rotating said wheels to bring said pins successively into the path of movement of the carrier-rod, said wheel-rotating means comprising two slidable members carrying pawls engaging said wheels, and means for moving said members alternately to cause said pawls to rotate said wheels alternately.

2. In a knitting machine, mechanism for producing striping designs or patterns in hosiery, including a reciprocating carrier-rod equipped with thread-carriers, a pattern wheel for limiting the movement of the carrier-rod in one direction, a similar wheel for limiting the movement of the carrier-rod in the other direction, each wheel being adapted to carry an annular series of removable pins of differing lengths, means for rotating said wheels to bring said pins successively into the path of movement of the carrier-rod, said wheel-rotating means comprising two slidable members carrying pawls engaging said wheels, trippable elements pivotally secured to said members at one end thereof, a reciprocating body adapted to contact with said trippable elements to move them and said slidable members to cause said pawls to rotate said wheels, and means for moving said trippable elements alternately out of the path of movement of said body.

3. In a knitting machine, mechanism for producing striping designs or patterns in hosiery, including a reciprocating carrier-rod equipped with thread-carriers, a pattern wheel for limiting the movement of the carrier-rod in one direction, a similar wheel for limiting the movement of the carrier-rod in the other direction, each wheel being adapted to carry an annular series of removable pins of differing lengths, means for rotating said wheels to bring said pins suc-

cessively into the path of movement of the carrier-rod, said wheel-rotating means comprising two slidable members carrying pawls engaging said wheels, trippable elements pivotally secured to said members at one end thereof, a reciprocating body adapted to contact with said trippable elements to move them and said slidable members to cause said pawls to rotate said wheels, cam-actuated mechanism for reciprocating said body, and means for moving said trippable elements alternately out of the path of movement of said body.

4. In a knitting machine, mechanism for producing striping designs or patterns in hosiery, including a reciprocating carrier-rod equipped with thread-carriers, a pattern wheel for limiting the movement of the carrier-rod in one direction, a similar wheel for limiting the movement of the carrier-rod in the other direction, each wheel being adapted to carry an annular series of removable pins of differing lengths, means for rotating said wheels to bring said pins successively into the path of movement of the carrier-rod, said wheel-rotating means comprising two slidable members carrying pawls engaging said wheels, trippable elements pivotally secured to said members at one end thereof, a reciprocating body adapted to contact with said trippable elements to move them and the slidable members to cause said pawls to rotate said wheels, means for moving said trippable members alternately out of the path of movement of said body, and a chain-motion mechanism for intermittently moving both of said trippable elements simultaneously out of the path of movement of said body.

5. In a knitting machine, mechanism for producing striping designs or patterns in hosiery, including a reciprocating carrier-rod equipped with thread-carriers, a pattern wheel for limiting the movement of the carrier-rod in one direction, a similar wheel for limiting the movement of the carrier-rod in the other direction, each wheel being adapted to carry an annular series of removable pins of differing lengths, means for rotating said wheels to bring said pins successively into the path of movement of the carrier-rod to vary the stroke thereof, said wheel-rotating means comprising two slidable members carrying pawls engaging said wheels, trippable elements pivotally secured to said members at one end thereof, a reciprocating body adapted to contact with said trippable elements to move them and said slidable members to cause said pawls to rotate said wheels, means for moving said trippable elements alternately out of the path of movement of said body, and means for intermittently moving both of said trippable elements simultaneously out of the path of movement of said body.

6. In a knitting machine, mechanism for producing striping designs or patterns in hosiery, including a reciprocating carrier-

rod equipped with thread-carriers, a pattern wheel for limiting the movement of the carrier-rod in one direction, a similar wheel for limiting the movement of the carrier-rod in the other direction, each wheel being adapted to carry an annular series of removable pins of differing lengths, means for rotating said wheels to bring said pins successively into the path of movement of the carrier-rod to vary the stroke thereof, said wheel-rotating means comprising two slidable members carrying pawls engaging said wheels, trippable elements pivotally secured to said members at one end thereof, a reciprocating body adapted to contact with said trippable elements to move them and the slidable members to cause said pawls to rotate said wheels, means for moving said trippable members alternately out of the path of movement of said body, and a chain-motion mechanism for intermittently moving both of said trippable elements simultaneously out of the path of movement of said body.

7. In a knitting machine, mechanism for producing striping designs or patterns in hosiery, including a reciprocating carrier-rod equipped with thread-carriers, a pattern wheel for limiting the movement of the carrier-rod in one direction, a similar wheel for limiting the movement of the carrier-rod in the other direction, each wheel being adapted to carry an annular series of removable pins of differing lengths, means for rotating said wheels to bring said pins successively into the path of movement of the carrier-rod to vary the stroke thereof, said wheel-rotating means comprising two slidable members carrying pawls engaging said wheels, trippable elements pivotally secured to said members at one end thereof, a reciprocating body adapted to contact with said trippable elements to move them and the slidable members to cause said pawls to rotate said wheels, means for moving said trippable members alternately out of the path of movement of said body, and a chain-motion mechanism, actuated by the wheel-rotating means, for intermittently moving both of said trippable elements simultaneously out of the path of movement of said body.

8. In a knitting machine, mechanism for producing striping designs or patterns in hosiery, including a reciprocating carrier-rod equipped with thread-carriers, a pattern wheel for limiting the movement of the carrier-rod in one direction, a similar wheel for limiting the movement of the carrier-rod in the other direction, each wheel being adapted to carry an annular series of removable pins of differing lengths, means for rotating said wheels to bring said pins successively into the path of movement of the carrier-rod to vary the stroke thereof, said wheel-rotating means comprising two slida-

- ble members carrying pawls engaging said wheels, trippable elements pivotally secured to said members at one end thereof, a reciprocating body adapted to contact with said trippable elements to move them and the 5 slideable members to cause said pawls to rotate said wheels, means for moving said trippable members alternately out of the path of movement of said body, a chain-motion mechanism for intermittently moving both of said trippable elements simultaneously out of the path of movement of said body, and manually-operated means for operatively connecting said chain-motion mechanism to said wheel-rotating means so as to be 10 actuated by the latter.
9. In a knitting machine, mechanism for producing striping designs or patterns in hosiery, including a reciprocating carrier-rod equipped with thread-carriers, a pattern wheel for limiting the movement of the carrier-rod in one direction, a similar wheel for limiting the movement of the carrier-rod in the other direction, each wheel being adapted 15 to carry an annular series of removable pins of differing lengths; means for rotating said wheels to bring said pins successively into the path of movement of the carrier-rod to vary the stroke thereof, said wheel-rotating means comprising two slideable members carrying pawls engaging said wheels, trippable elements pivotally secured to said members at one end thereof, a reciprocating body adapted to contact with said trippable elements to move them and the slideable members to cause said pawls to rotate said wheels, means for moving said trippable members alternately out of the path of movement of said body, a chain-motion mechanism for intermittently moving both of said trippable elements simultaneously out of the path of movement of said body, and a pivoted dog carried by said wheel-rotating means and engageable with said chain-motion mechanism for causing said wheel-rotating means to actuate said chain-motion mechanism.
10. In a knitting machine, mechanism for producing striping designs or patterns in hosiery, including a reciprocating carrier-rod equipped with thread-carriers, a pattern wheel for limiting the movement of the carrier-rod in one direction, a similar wheel for limiting the movement of the carrier-rod in the other direction, each wheel being adapted 20 to carry an annular series of removable pins of differing lengths; means for rotating said wheels to bring said pins successively into the path of movement of the carrier-rod to vary the stroke thereof, said wheel-rotating means comprising two slideable members carrying pawls engaging said wheels, trippable elements pivotally secured to said members at one end thereof, a reciprocating body adapted to contact with said trippable elements to move them and the slideable members so as to cause said pawls to rotate said wheels, means for moving said trippable members alternately out of the path of movement of said body, a chain-motion mechanism for intermittently moving both of said trippable elements simultaneously out of the path of movement of said body and comprising two sprocket-wheels and an endless chain passing thereover and carrying a longitudinally-arranged series of lugs, and a lever having one end disposed adjacent said trippable elements and its other end adjacent said chain so as to be intermittently rocked as said lugs successively contact therewith.
11. In a knitting machine, mechanism for producing striping designs or patterns in hosiery, including a reciprocating carrier-rod equipped with thread-carriers, a pattern wheel for limiting the movement of the carrier-rod in one direction, a similar wheel for limiting the movement of the carrier-rod in the other direction, each wheel being adapted 25 to carry an annular series of removable pins of differing lengths; means for rotating said wheels to bring said pins successively into the path of movement of the carrier-rod to vary the stroke thereof, said wheel-rotating means comprising two slideable members carrying pawls engaging said wheels, trippable elements pivotally secured to said members at one end thereof, a reciprocating body adapted to contact with said trippable elements to move them and the slideable members so as to cause said pawls to rotate said wheels, means for moving said trippable members alternately out of the path of movement of said body, a chain-motion mechanism for intermittently moving both of said trippable elements simultaneously out of the path of movement of said body and comprising two sprocket-wheels and an endless chain passing thereover and carrying a longitudinally-arranged series of lugs, and a lever having one end disposed adjacent said trippable elements and its other end adjacent said chain so as to be intermittently rocked as said lugs successively contact therewith.
12. In a knitting machine, the combination with a reciprocating carrier-rod equipped with thread-carriers slideable in a direction transverse of said carrier-rod, a slide disposed transversely of said thread-carriers, co-operating means carried by said slide and thread-carriers for holding the latter in lowered or operative position, and spring means for moving the thread-carriers to upper or inoperative position upon disengagement of said co-operating means.
13. In a knitting machine, the combination with a reciprocating carrier-rod equipped with thread-carriers slideable in a direction transverse of said carrier-rod, said thread-carriers being provided with

- projections toward their upper ends, a slide disposed transversely of said thread-carriers and carrying means co-operating with said projections to hold the thread-carriers in lowered or operative position, and spring means for moving the thread-carriers to upper or inoperative position when said slide-carried means are disengaged from said projections.
14. In a knitting machine, the combination with a reciprocating carrier-rod equipped with thread-carriers slidable in a direction transverse of said carrier-rod, said thread-carriers being provided with projections toward their upper ends, a slide disposed transversely of said thread-carriers and equipped with blocks co-operating with said projections to hold the thread-carriers in lowered or operative position, and spring means for moving said thread-carriers to upper or inoperative position when said projections and blocks are disengaged.
15. In a knitting machine, the combination with a reciprocating carrier-rod, a member extending longitudinally thereof and provided with a plurality of transverse grooves, thread-carriers slidable in said grooves, a slide disposed transversely of said thread-carrier, co-operating means carried by said slide and said thread-carriers for holding the latter in operative position, and spring means for moving said thread-carriers to upper or inoperative position when said co-operating means are disengaged.
16. In a knitting machine, the combination with a reciprocating carrier-rod, a member extending longitudinally of said carrier-rod, thread-carriers slidably supported upon said member, a slide disposed transversely of said thread-carriers, co-operating means carried by said slide and said thread-carriers for holding the latter in operative position, and spring means connected with said thread-carriers for moving them to inoperative position when said co-operating means are disengaged.
17. In a knitting machine, the combination with a reciprocating carrier-rod, a member extending longitudinally thereof, thread-carriers slidably supported upon said member and provided with projections, a slide disposed transversely of said thread-carriers and carrying spaced elements engageable with said projections to hold said thread-carriers in operative position, and spring means connected with said thread-carriers for moving them to inoperative position when said elements are not in engagement with said projections.
18. In a knitting machine, the combination with a reciprocating carrier-rod equipped with thread-carriers slidable in a direction transverse of said carrier-rod, a slide disposed transversely of said thread-carriers, co-operating means carried by said slide and thread-carriers for holding the latter in lowered or operative position, and spring means associated with said thread-carriers for moving them into inoperative position upon disengagement of said co-operating means, and re-setting means for said thread-carriers adapted to force the latter downward.
19. In a knitting machine, the combination with a reciprocating carrier-rod equipped with thread-carriers slidable in a direction transverse thereof, said thread-carriers being provided at their upper ends with pins projecting beyond both faces of the thread-carriers, a slide disposed transversely of said thread-carriers and carrying members engageable with the pin-ends projecting from one face of the thread-carriers to hold the latter in operative position, spring means associated with said thread-carriers for moving them into inoperative position when said slide-members are disengaged from said pins, and re-setting means engageable with the pin-ends projecting from the opposite face of the thread-carriers.
20. In a knitting machine, the combination with a reciprocating carrier-rod equipped with thread-carriers slidable in a direction transversely thereof, said thread-carriers being provided at their upper ends with pins projecting beyond both faces of the thread-carriers, a slide disposed transversely of said thread-carriers, blocks removably secured to said slide and engageable with the pin-ends projecting from one face of the thread-carriers to hold the latter in operative position, spring means associated with said thread-carriers for moving them into inoperative position when said blocks are disengaged from the pin-ends, and re-setting means engageable with the pin-ends projecting from the opposite face of the thread-carriers.
21. In a knitting machine, the combination with a reciprocating carrier-rod equipped with thread-carriers slidable in a direction transversely thereof, said thread-carriers being provided at their upper ends with pins projecting beyond both faces of the thread-carriers, a slide disposed transversely of said thread-carriers, blocks removably secured to said slide and engageable with the pin-ends projecting from one face of the thread-carriers to hold the latter in operative position, spring means associated with said thread-carriers for moving them into inoperative position when said blocks are disengaged from the pin-ends, a re-setting member engageable with the pin-ends projecting from the opposite face of the thread-carriers, and pivoted supporting means for said re-setting member.
22. In a knitting machine, the combination with a reciprocating carrier-rod

equipped with thread-carriers slidable in a direction transverse of said carrier-rod, a slide disposed transversely of said thread-carriers, co-operating means carried by said slide and thread-carriers for holding the latter in lowered or operative position, spring means for moving said thread-carriers to upper or inoperative position upon disengagement of said cooperating means, and manually-actuated means for moving said slide step by step.

23. In a knitting machine, the combination with a reciprocating carrier-rod

equipped with thread-carriers slidable in a direction transverse of said carrier-rod, a slide disposed transversely of said thread-carriers, co-operating means carried by said slide and thread-carriers for holding the latter in operative position, spring means for moving said thread-carriers to inoperative position upon disengagement of said cooperating means, and a lever for moving said slide step by step.

In testimony whereof, I hereunto affix my signature.

LEON KLEIN.
